COMBINED DISPLAY PACKAGE AND DISPENSER FOR CORELESS ROLLS OF DECORATIVE RIBBON

Myer Gorman, Leonia, N.J., assignor to Sun Chemical Corporation, New York, N.Y.

Filed July 26, 1972, Ser. No. 275,450

Term of patent 14 years

Int. Cl. D9—03

U.S. Cl. D9—192

FIG. 1

FIG. 2

FIG. 1 is a front perspective view of a combined display package and dispenser for coreless rolls of decorative ribbon showing my new design; and

FIG. 2 is a rear perspective view thereof in a partially opened and dispensing condition.

The dotted line represents perforations.

I claim:

The ornamental design for a combined display package and dispenser for coreless rolls of decorative ribbon, substantially as shown and described.
